UNITED STATES PATENT OFFICE.

JAMES M. PRICE, OF PHILADELPHIA, PENNSYLVANIA.

SUPPORT FOR RAILROAD-RAILS.

SPECIFICATION forming part of Letters Patent No. 430,590, dated June 17, 1890.

Application filed December 3, 1888. Serial No. 292,486. (No model.)

To all whom it may concern:

Be it known that I, JAMES M. PRICE, a citizen of the United States, residing in the city and county of Philadelphia, State of Pennsylvania, have invented a new and useful Improvement in Supports for Railroad-Rails, which improvement is fully set forth in the following specification and accompanying drawings.

10 My invention consists of means for supporting railroad-rails in lieu of wooden cross-ties and stringers, the same embodying trusses formed of metal, as will be hereinafter fully set forth and claimed.

15 It also consists of means, substantially as described, for connecting the stringers, whereby the same are braced in lateral directions and prevented from spreading.

It also consists of means, substantially as 20 described, for connecting the rails with the stringers in a firm and durable manner.

It also consists of means, substantially as 25 described, whereby the head and foot or members of each truss of the stringer are strengthened.

It also consists of the construction and combination of various parts, as will be described and claimed, adapting the stringers for elevated roads, street-car tracks, bridges, 30 &c.

Figure 1 represents a side elevation of a support for a railroad-rail embodying my invention. Fig. 2 represents a transverse vertical section on line $x-x$, Fig. 1. Fig. 3 represents a top or plan view thereof. Figs. 4 and 5 represent transverse vertical sections of modifications on enlarged scales. Fig. 6 represents a perspective view of a bed on which the rail is supported and the means 35 for clamping the said rail. Fig. 7 represents a side elevation of the truss serviceable for elevated roads, bridges, &c. Fig. 8 represents a transverse vertical section thereof on line $y-y$, Fig. 7. Fig. 9 represents a side elevation of a form of truss serviceable for street-rails. Fig. 10 represents a transverse section thereof on line $z-z$, Fig. 9. Figs. 11 and 40 12 represent vertical sections of modifications. Fig. 13 represents a horizontal section on line $a-a$, Fig. 12. Figs. 14 and 15 represent side elevations of couplings for the

members of the trussed stringer embodying my invention.

Similar letters and numerals of reference indicate corresponding parts in the several 55 figures.

Referring to the drawings, A designates stringers on which railroad-rails are supported, the same being formed of suitable metal bent or rolled into the shape of trusses 60 or alternately inverted, producing the heads 1, to which the rails are secured, and feet 2 as the bases of the stringers.

C C' designate transversely-extending clamps, which are secured, respectively, to the 65 heads and bases of the trusses of the stringers, said clamps being also formed with cheek-pieces 3, which embrace the outer sides of the heads 1 and the bases of the rails. The inner sides of said heads are connected with clamps 70 C by means of bolts 4, whose heads bear against the flanges of the rails on the sides opposite to the cheek-pieces 3, by which means the rails are firmly connected with the trusses, and the upper parts of the pair of 75 stringers are held properly apart. The clamps C' are secured to the feet of the trusses by means of rivets or bolts 5, whereby in connection with the clamps C the pair of stringers are held properly apart and braced and 80 strengthened in lateral directions, thus producing a strong structure. The stringers will be suitably ballasted, as shown in Fig. 1, whereby the heads of the trusses will receive additional support, and thereby be better enabled to endure the strain superimposed upon 85 the same.

In order to provide a wider footing for the stringers upon the ballast underneath, I employ bars 6, which are channeled to receive 90 the bases of the trusses and extend in transverse direction, connecting the pair of stringers, and are connected thereto, as seen in Fig. 3, one of said bars being shown in side elevation by the dotted figure at the right of said 95 Fig. 3.

In Figs. 1, 2, and 3 the stringers are shown as formed of flat metal with channels 7 on the upper faces of the heads of the stringers to receive the bases of the rails.

In Fig. 4 the stringers are shown made of round metal, and in Fig. 5 they are shown

made of angle-iron. Interposed between the bases of the rails and the trussed stringers in said Figs. 4 and 5 are bed-plates 9, (see also Fig. 6,) the same resting on the heads of the 5 stringers or trusses and being bolted or otherwise secured thereto. The clamps C C' in these cases are grooved on their upper and under sides to receive, respectively, the heads and feet of the trusses, the ends of the clamps 10 having cheek-pieces 3, which embrace the bed-pieces and base of the rails, which, in connection with removable cheek-pieces 10 opposite to the cheek-pieces 3 and bolts 11, firmly connect the rails, bed-pieces, and 15 clamps with the trusses. Connected with the heads and feet of the trusses, as in Figs. 7, 8, 9, and 10, are additional stringers D D', which extend in the longitudinal direction of the same, and are bolted or riveted thereto, 20 adapting the stringers for elevated roads and bridges and without ballast for street use.

The rail in Figs. 7 and 8 rests in the stringer D, and the clamps C embrace the heads 1 of the trusses, the base of the rail, and 25 the additional stringer D, the several parts being properly bolted together on each side of the flange.

In Figs. 9 and 10 the additional stringer D is shown as supporting a street-car rail.

30 In Figs. 11 and 12 the heads 1 of the trusses are shown in section heavily shaded, with shoulders and grooves on their upper and lower faces, so as to interlock with the clamps C and cheek-pieces 12 of the rail-fastening.

35 Each truss in Figs. 1, 2 and 3 is formed in one piece, the heads and feet thereof being contiguous to each other; but where the members of the trusses are made separate, or where two stringers come together, they are 40 connected by coupling-pieces 13, as in Figs. 14 and 15, the ends of the feet or of the heads, or both, being secured to said pieces.

The flat stringers, Figs. 1, 2, and 3, may be constituted of one or more pieces, as seen 45 in transverse section, moving longitudinally of the track and bound together by clamp and bed plates, as hereinafter described.

The stringers A may be rolled or produced in any other suitable manner in long or short 50 sections or pieces or individual trusses connected according to the length required, it being seen that the stringers present a structure which in longitudinal direction is of the form of crimps or corrugations, arches and 55 reversed arches, or truncated pyramids and reversed truncated pyramids, thereby producing a strong and firm support for the rails, the same being vastly more durable than wooden ties and stringers, one that may 60 be quickly and easily laid and is not of expensive nature, is uniformly elastic, and causes smoothness of running the cars thereon. Owing to the uniform elasticity of every 65 section of these stringers, whether the flat summit or the flat base of any section corresponding to the wooden cross-tie in its function is midway of the section or not, the joint

of the rails may be advantageously made on these summits instead of between cross-ties, as commonly done to insure the needful elasticity. 70

To prevent the rails from sliding longitudinally upon the summits because of not being bolted together through transverse holes in the web, I notch the flange of each rail near 75 its end, and thus two projections or nipples on the underside of the broad cheek-piece or track-plate, Fig. 13, engage with these notches or slots in the flange of each rail, permitting 80 but limiting the expansion and contraction of the rails. This secures a continuous rail without using the expensive fish-plates now employed and without piercing the web.

Having thus described my invention, what I claim as new, and desire to secure by Letters Patent, is—

1. As a new article of manufacture, a trussed metallic stringer with longitudinal ridges and a central depression and formed in transverse corrugations of parallel summit and 90 base, substantially as described.

2. A stringer for supporting a railroad-rail, formed of metal with longitudinal ridges or elevations and depressions and crimped or corrugated transversely into trusses shaped 95 like a truncated pyramid alternately inverted, substantially as described.

3. A trussed metallic stringer with a longitudinal ridge at each edge, forming a countersunk bed for the rail, in combination with 100 transverse clamps for holding the rail in place, substantially as described.

4. A trussed metallic stringer, in combination with base-bars 6, substantially as described. 105

5. A metallic stringer formed of trusses the members whereof are connected by couplings, such as 13, substantially as described.

6. A trussed metallic stringer, with bed for the rail confined by longitudinal ridges and 110 its edges raised to give a bearing for the clamps and cheek-pieces, substantially as described.

7. A trussed metallic stringer having coupling-pieces with grooves in which the end of 115 the stringer fits, substantially as described.

8. A metallic stringer formed of trusses, in combination with a clamp, and with a bed-plate intermediate of the rail and truss, said clamp connecting the rail, bed-plate, and truss, 120 substantially as described.

9. A trussed metallic stringer transversely corrugated into truncated pyramids connected at the base, in combination with a rail above and a horizontal stretcher below running longitudinally, and with transverse clamps for securing the rails, substantially 125 as described.

10. A trussed metallic stringer corrugated transversely into truncated pyramids, with an 130 elevated edge on each outer surface running longitudinally, in combination with clamps and cheek-pieces to which the elevated edges give a bearing, holding their inner surfaces

firmly against the edge of the flange and the web of the rail, substantially as described.

11. A trussed metallic stringer, a lower connecting-rod receiving the base of said stringer, 5 and upper connecting-rod receiving the top of said stringer, and rails seated in the top of the stringer and retained thereon by the tie-rod and fastenings, substantially as described.

12. A trussed metallic stringer, a connecting-rod having recesses to receive the base of 10 the stringer and lips for embracing the outer edges thereof, a connecting-rod having recesses to receive the top of the stringer, and lips for embracing the outer edges thereof and the outer flanges of the rails, substantially in the 15 manner and for the purpose described.

13. A trussed metallic stringer having elevations and depressions, in combination with a bed-plate resting on one of said elevations 20 and a clamp adapted to embrace said bed-plate and stringer, substantially as and for the purpose set forth.

14. A trussed metallic stringer, tie-rods connected to the base and the top of the stringer, 25 bolts for securing the tie-rods to the base of

the stringer, and a cheek-piece on the upper tie-rod for engaging the stringer and rails, substantially in the manner and for the purpose described.

15. The combination of the metallic stringers A, each having the heads 1 and the feet 2, with the clamps C and C' and the bar 6, having channelled ends, substantially as described. 30

16. A trussed metallic stringer, a tie-rod connected to the base thereof, a bolt and clamp 35 for securing the tie-rod in place, a bed-plate resting on the stringer, and a tie-rod embracing the same and having cheek-pieces for engaging the flange of the rail, substantially in the manner and for the purpose described. 40

17. A trussed metallic stringer, tie-rods connected to the top and base thereof, a bolt for securing the tie-rod at the base, and a bed-plate supported on the top of the members and the upper tie-rod, substantially in the 45 manner and for the purpose described.
